A. M. SEEGER

HYDROCARBON BURNER

Filed April 27, 1927

UNITED STATES PATENT OFFICE.

ADOLPH M. SEEGER, OF TOLEDO, OHIO, ASSIGNOR OF ONE-HALF TO J. SHOWLES
MACLEAN, OF TOLEDO, OHIO.

HYDROCARBON BURNER.

Application filed April 27, 1927. Serial No. 186,853.

My invention has for its object to provide an efficient hydrocarbon burner which is so constructed that it will gasify the fuel at a very high temperature and maintain the fuel in an attenuated state within the burner while it is being mixed with air under pressure. The invention also provides for the addition of air at a high temperature whereby a perfect combustion is brought about. 5 Burners containing my invention are also so constructed that owing to the high temperature at which the hydrocarbon is subjected to, a water gas may be formed by causing a mixture of and reaction with steam which 10 is introduced in the heated hydrocarbon. 15

The invention may be contained in structures of different forms and to illustrate a practical application of the invention, I have selected two forms of burners illustrating 20 embodiments of my invention and shall describe them hereinafter. The constructions selected as examples are shown in the accompanying drawings.

Fig. 1 illustrates a side view of one form 25 of burner. Fig. 2 is a top view of the device illustrated in Fig. 1. Fig. 3 is a view of a section taken on the plane of the line 3—3 indicated in Fig. 1. Fig. 4 is a side view of 30 the other form of burner selected as an example. Fig. 5 is a top view of the burner shown in Fig. 4.

In the particular constructions shown in the drawing, the burners are provided with a hemispherical bowl into which the hydrocarbon, in the form of oil, is introduced, and a tip, or nozzle, communicating with the bowl is directed towards the bowl which produces a flame that covers the top of the bowl in the form of an inverted mushroom. In 35 the form of burner shown in Fig. 1 a hemispherical bowl 1 is connected to a suitable source of supply of oil by means of a pipe 2 that is threaded into an opening formed in the bottom of the bowl. A pipe 3, made in 40 the form of a goose neck and, preferably, cast integral with the bowl, extends upwards from one side of the bowl and over the top of the bowl. A passage-way 4 of the pipe 3 leads from one side of the bowl chamber, as indicated in dotted lines in Fig. 1. The interior and the exterior diameters of the pipe 45 50 55 60 65 70 75 80 85 90 95 100 105 3 are substantially as shown in Fig. 1. The bottom of the interior of the pipe 3 has communicating therewith an opening 5 of very

small bore and a pipe 6 communicates 55 through this passage-way with the pipe 3. The pipe 6 may be connected with a source of air under pressure in order to force air at a very rapid rate of movement through the opening 5 into the pipe 3. The pipe 3 being located at one side of the chamber of the hemispherical bowl 1, the movement of the air through the passage-way 5 increases the rate of movement of the gas from the bowl and at the same time produces a thorough mixture of the air with the gas in the pipe 3. This causes both the air and gas to thoroughly mix and to move towards the outlet at the upper end of the pipe 3. The pipe three terminates in a spherical head 10 70 that has a relatively large spherical chamber 11. An opening is provided in the lower part of the head 10 and a threaded sleeve 12 is threaded into the opening. The upper end of the sleeve 12 is tapered as at 13 and is 75 provided with a small opening 14, through which the mixture of air and gas passes with considerable velocity, and a nozzle, or tip, 15 is threaded onto the sleeve 12. The nozzle 15 is, preferably, in the form of an inverted frustum and is provided with the openings 16 in its upper end through which the air enters. The air is drawn into the nozzle 15 by the moving mixture of air and gas as it leaves the head 10. The nozzle 15 terminates with a short cylindrical end 17 which forms the outlet of the mixture of gases. The sleeve 12 extends well within the nozzle 15 and in the region of the cylindrical portion of the nozzle which produces 80 a Venturi action. This produces a rapid movement of the gases, namely, the auxiliary air through the opening 16 and the mixture of air and gas from the head 10 of the pipe 3. If the gases are ignited, the flame 85 is directed towards the top of the bowl 1 and spreads over the surface of the top in the form of an inverted mushroom, or toadstool, which raises the bowl 1 to a very high temperature and maintains it at all times. Furthermore, the tip, or nozzle, of the burner being located above the flame the gases 90 that pass through the pipe 3 and the head 10 are also maintained at a very high temperature and the air that enters through the 95 openings 16 is highly heated.

The top of the bowl 1 is, preferably, formed sloping, which slopes the interior

upper surface of the bowl towards the passage-way 4 of the pipe 3. Preferably, the top of the bowl is provided with a ridge which slopes towards opposite edges of the bowl. The ridge 20 extends diametrically from the edge of the bowl to the pipe 3.

If desired steam may be introduced through the pipe 6 when the temperature of the gases within the bowl has been raised to a very high point. This will cause the desired rapid movement of the gas and if the temperatures are raised to a sufficiently high point, a form of water gas may be produced.

In the operation of the burner the bowl 1 may be filled with oil and as the flame intensifies in heat the surface of the oil will be forced back by pressure of the gas that is created by the heat. But as the gasified oil escapes new oil will be continuously fed into the bowl and subjected to the intensity of the heat produced by the flame. The gases will raise to the sloping surface of the top of the bowl and be more intensely heated when they will escape through the pipe 3 and their movement accentuated by the injection of the air or steam through the narrow passage-way 5. Auxiliary air will be drawn through the opening 16 and mixed in the Venturi shaped nozzle as the gas passes through the throat of the nozzle and so as to produce a perfect combustion as the gases are carried down to the top of the bowl 1.

In order to start the burner a combustible liquid may be inserted in the trough 21 which surrounds the sides of the hemispherical bowl 1.

In the form of burner shown in Figs. 4 and 5, a plurality of nozzles 15 are supported on the heads 10 of the pipes 25 that are also arranged circumferentially around the edge of the bowl 26. The interior passage-way of the pipes 25 communicate with the interior of the bowl 26, the pipes being located so that the axes of the pipes 25 will be located substantially in line with the small openings 27, which communicate with the pipe 28. The pipe 28 may be connected with the source of air under pressure. The arrangement is such that the same conditions are produced which the outlets of the nozzles 15 will produce in the form of construction shown in Fig. 1.

The top of the hemispherical bowl 26 may be provided with a central cone portion 29 that terminates in a pipe 30. A pipe 31 extends into the pipe 30. The pipe 31 may be connected with the source of supply of steam. The nozzles 15 are so located as to direct the flame that is formed towards the cone 29 and raise the gases within the cone to a very high temperature. The gases will rise through the pipe 30 and the steam which passes through the pipe 31 will mix

with the gases producing a form of water gas which may be drawn off from the pipe 30.

The lower end of the bowl 26 is provided with a connector 32 through which the pipe 31 extends and which is connected to the pipe 33 through which oil may be directed into the bowl 26. The operation of the burner shown in Figs. 4 and 5 is substantially the same as that of the operation of the burner shown in Fig. 1, except that the steam is introduced through a central pipe 30 leading from the cone 29. The heat of the flames projected from the nozzles 15 centers on the cone 29 to raise it to a very high temperature. The resultant gas that is thus produced is rendered permanent by the introduction of the steam as against the action of cooling and, consequently, gas may be conveyed to other heating devices or burners.

I claim:

1. In a burner, a container for containing a considerable quantity of liquid hydrocarbon fuel, the burner having a passage-way extending to a point well above the container, the upper end of the passage-way terminating in a spherical chamber having a diameter larger than the diameter of the passage-way, a sleeve having a relatively large bore and a small opening forming a communication between the interior of the sleeve and the spherical chamber, the said opening located in the central portion of the chamber, and a nozzle connected to the sleeve.

2. In a burner, a container for containing a considerable quantity of liquid hydrocarbon fuel, the burner having a passage-way extending to a point well above the container, a nozzle communicating with the passage-way and directed towards the container for heating the container at a high temperature, the burner having a passage-way that is relatively much smaller than the first named passage-way and communicating with the first named passage-way at its lower end and extending in the same direction as the first named passage-way, a pipe for directing air under pressure through the last named passage-way and into the first named passage-way, the first named passage-way terminating in a spherical chamber, a sleeve having a relatively large bore and a small opening forming a communication between the bore of the sleeve and the spherical chamber, the said opening located in the central portion of the chamber and a nozzle connected to the sleeve.

3. In a burner, a container for containing a considerable quantity of liquid hydrocarbon fuel, the burner having a passage-way extending to a point well above the container, the upper end of the passage-way

terminating in a spherical chamber having a diameter larger than the diameter of the passage-way, a sleeve having a relatively large bore and a small opening forming a communication between the interior of the sleeve and the spherical chamber, the said opening located in the central portion of the chamber, a nozzle connected to the sleeve, the nozzle having an interior Venturi shape, 10 openings located at the ends of the nozzle and the sleeve terminating in the region of the throat of the Venturi shaped interior of the nozzle.

4. In a burner, a container for containing 15 a considerable quantity of liquid hydrocarbon fuel, the burner having a passage-way extending to a point well above the container, the upper end of the passage-way ter-

minating in a spherical chamber having a diameter larger than the diameter of the 20 passage-way, a sleeve having a relatively large bore and a small opening forming a communication between the interior of the sleeve and the spherical chamber, the said opening located in the central portion of the 25 chamber, a nozzle connected to the sleeve, the nozzle having an interior Venturi shape, openings located at the ends of the nozzle and the sleeve terminating in the region 30 of the throat of the Venturi shaped interior of the nozzle, and the top of the container inclined to the horizontal and extending upwardly towards the passage-way.

In witness whereof I have hereunto signed my name to this specification.

ADOLPH M. SEEGER.
